DUAL MOVABLE SASH WINDOW

Abraham Grossman, 9339 Rhea St., Northridge, Calif.
Filed Sept. 26, 1960, Ser. No. 58,229
4 Claims. (Cl. 20—52)

This invention relates to a dual, movable sash window and, more particularly, to means for sealing said sash of said window and the frame thereof against infiltration of air, moisture and dirt in a more effective manner than has been previously thought possible.

The principles of the invention, while illustrated as embodied in a double sliding sash horizontal window are, as will be obvious to those skilled in the art, applicable with equal cogency to doors incorporating dual sliding sash of the same general construction as the sliding sash incorporated in the window disclosed hereinbelow.

One of the greatest problems encountered in the effective operation of dual sliding sash windows is the infiltration of air, dirt and moisture between the overlapping stiles of the sash and between the lower rails of the sash. It is, therefore, an object of my invention to provide a window incorporating dual sliding sash in a horizontal frame which is characterized by the provision of a complete seal between the interlocking stiles on said sash so that the infiltration of air, dirt and moisture at the extremities of said interlocking stiles is prevented.

It is customary, in windows of the aforementioned character, to provide the interlocking stiles of the sliding sash with clearance openings or cuts at the upper and lower extremities of the interlocking portions of the stiles so that the sash may be readily removed from or installed in the inner and outer channels of the window frame. The clearance openings or cuts in the opposite extremities of the interlocking portions of the stiles are adapted to receive the intermediate wall between the inner and outer channels of the frame when the sash are installed in or removed from the frame.

In prior art constructions no effective seal for these clearance openings has been provided and, therefore, the clearance openings have constituted passageways at the upper and lower extremities of the overlapping stiles of the sliding sash for the infiltration of dirt, moisture and air into the room where the window is installed.

It is, therefore, another object of my invention to provide a continuous weatherstrip between the overlapping stiles of the sliding sash which extends from one extremity to the other of one of the interlocking stiles and which thus covers the clearance openings in the upper and lower extremities of the interlocking portions of said stiles. Therefore, the infiltration of air, dirt and moisture through said openings is prevented.

Another of the major problems encountered in horizontal sliding windows is the drainage of moisture from the inner channel of the sill portion of the window frame since, during rainy weather or during periods of high humidity or fog, considerable quantities of moisture accumulate in the inner channel. The customary expedient utilized to cope with this problem is the provision of a plurality of drainage openings in the outer wall of the inner channel which permits moisture to drain into the outer channel and from said outer channel into drain openings communicating with the exterior of the building in which the window is installed.

Unfortunately, it has been discovered that the drain openings in the outer wall of the inner channel constitute passageways for the infiltration of air, dirt and moisture into the room with which the window is associated and thus, while permitting drainage of moisture, the openings also serve to create draft and dirt problems.

It is a further object of my invention to provide a window having a frame incorporating drainage openings

2

from the inner channel similar to those provided in conventional window frame constructions. To prevent the infiltration of air and dirt into the room, I provide an auxiliary weatherstrip which overlies the upper extremities of the drainage openings and which, while permitting the efflux of moisture from the inner channel, prevents the ingress of air and dirt into the inner channel and thus into the interior of the room with which the window is associated.

10 A further object of my invention is the provision of a window of the aforementioned character wherein the elongated weatherstrip associated with said drain openings incorporates a plurality of filamentary bodies, said filamentary bodies serving, by capillary action, to induce the efflux of moisture collecting in the inner channel through the drain openings.

Other objects and advantages of the invention will be apparent from the following specification and the accompanying drawing, which is for the purpose of illustration only and in which:

FIG. 1 is a front elevational view of a window constructed in accordance with the teachings of my invention;

25 FIG. 2 is an enlarged, vertical, fragmentary sectional view showing related portions of the inner and outer sliding sashes;

FIG. 3 is a transverse sectional view taken on the broken line 3—3 of FIG. 1; and

30 FIG. 4 is a vertical sectional view taken on the broken line 4—4 of FIG. 1.

Referring to the drawing and particularly to FIGS. 1, 2 and 4 thereof, I show a window 10 constructed in accordance with the teachings of my invention, said window including a frame 12 which is constituted by a head 14, a sill 16 and jambs 18 and 20. The head 14, sill 16 and jambs 18 and 20 are maintained in operative relationship with each other by a steel strap 21, this particular construction being disclosed in my copending applications for United States Letters Patent, Serial No. 44,493, filed July 21, 1960, entitled "Window Frame Construction" and Serial No. 44,496, filed July 21, 1960, entitled "Method of Fabricating Window Frames."

The various components of the frame 12 are fabricated from extrusion shapes of identical configuration which, in the case of the sill 16, includes an inner channel 22 separated from an outer channel 24 by an intermediate wall 26. The head 14 is, of course, constituted by an extrusion of the same shape as the sill 16 including an inner channel 22, an outer channel 24 and the intermediate wall 26 therebetween.

An inner track 32 is disposed in the inner channel 22 and an outer track 34 is disposed in the outer channel 24 in the sill 16. The construction and function of the tracks 32 and 34 will be described in greater detail herebelow.

It will be noted that the intermediate wall 26, as best shown in FIGS. 2 and 3 of the drawings, incorporates drainage openings 36 adapted to drain moisture accumulating in the inner channel 22 into the outer channel 24 which has an elongated receptacle 38 in communication therewith. The wall of the elongated receptacle 38 is provided with a plurality of punch-outs 42 defining drain openings 43 to the exterior of the building in which the window 10 is installed. Therefore, the flow of moisture from the inner channel 22 through the drain openings 36 and through the elongated receptacle 38 to the drain openings 43 is as indicated by the series of arrows 44 in FIG. 2 of the drawing.

70 It should be pointed out that the opposite extremities of the outer track 34 terminate, as best shown in FIG. 1 of the drawing, inwardly of the extremities of the sill 16 and the outer channel 24. Therefore, the flow of mois-

ture actually follows a path from the drain openings 36 in the intermediate wall 26 along the adjacent surface of the track 34 to the opposite extremities of the track and thence through the drain openings 43 communicating with the receptacle 38.

Mounted for movement on the inner track 32 within the inner channel 22 of the sill 16 and the corresponding inner channel 22 of the head 14 is an inner sliding sash 50, said inner sliding sash including upper and lower rails 52 and 54, respectively, joined in operative relationship with each other by stiles 56 and 58, respectively. The rails 52 and 54 and the stiles 56 and 58 encompass a pane 62 of glass and rollers 64 mounted in the lower rail 54 of the movable sash 50 supporting the movable sash 50 upon the inner track 32.

The stile 58 of the inner sliding sash 50 is an interlocking stile, that is, it is provided with an interlocking portion or flange 68, as best shown in FIG. 3 of the drawing. The interlocking flange is provided with clearance openings or cuts 72 and 74 at its upper and lower extremities, as best shown in FIG. 4 of the drawing, said clearance openings being adapted to permit the movable sash 50 to be inserted in the frame 12 by clearing the intermediate wall 26 between the inner and outer channels 22 and 24, respectively, of the head 14 and the sill 16. A handle 76 is secured to the stile 58 of the inner movable sash 50 and, when grasped, permits said sash to be slid back and forth on the associated track 32.

An outer movable sash 80 is mounted for movement on the track 34 located in the outer channel 24 and includes top and bottom rails 82 and 84, respectively, and stiles 86 and 88. The bottom rail 84 includes rollers 94 engageable with the track 34 and adapted to facilitate the free sliding movement of the outer sash 80 upon said track. The stile 88 of the movable sash 80 adapted to overlie the corresponding stile 58 of the inner, movable sash is of the same configuration as the stile 58 and includes an interlocking flange 98 adapted to engage the corresponding interlocking flange 68 on the stile 58 of the inner movable sash 50.

The upper and lower extremities of the interlocking flange 98 are cut away, as best shown in FIG. 4 of the drawing, to provide clearance openings 102 and 104 at the upper and lower extremities of the stile 88, thus permitting the outer movable sash 80 to be installed in operative association with the frame 12 by clearing the intermediate walls 26 between the inner and outer channels 22 and 24 of the head 14 and the sill 16.

Mounted in an elongated vertical receptacle 119 in the stile 88 of the outer movable sash 80, as best shown in FIG. 3 of the drawing, is a continuous weatherstrip 120 which, as best shown in FIG. 4 of the drawing, extends from the top to the bottom of the stile 88 and thus overlies and seals off the clearance openings 72 and 74 in the stile 58 and the clearance openings 102 and 104 in the stile 88. Therefore, the infiltration of dirt and moisture and air through the clearance openings, which occurs in prior art constructions, is not encountered in the present construction. This is attributable to the fact that the elongated weatherstrip 120 is disposed on the stile 88 of the outer movable sash 80 outwardly of the interlocking flanges 68 and, thus, acts as a barrier to prevent the bypassing of air through the clearance openings in the upper and lower extremities of said flanges.

It will, of course, be noted that both the upper and lower rails of the inner and outer movable sashes 50 and 80 are provided with elongated weatherstrips 124 which engage adjacent areas of the intermediate wall 26 and serve to restrict the infiltration of air and moisture and dirt past said wall.

It will be noted that the inner track 32 and the outer track 34 are constituted by plastic extrusions which are snapped into the inner channel 22 and the outer channel 24, respectively. However, of course, it is not intended to limit the teachings of the invention to any particular

type of track since it is obvious that the extrusion constituting the sill 16 may be provided with integral track or other alternative expedients.

In any event, the elongated outer track 34 has a continuous weatherstrip 130 mounted thereupon which is formed from mohair or other filamentary material and which, as best shown in FIG. 2 of the drawing, extends along the base of the intermediate wall 26 and overlies the drain openings 36 in the bottom of said wall. Therefore, the elongated weatherstrip 130 acts as a barrier against the infiltration of air and dirt through the drain openings 36 into the interior of the room in which the window 10 is located.

Moreover, the filaments constituting the weatherstrip 130 serve, by capillarity, to induce the outward flow of moisture collected in the inner channel 22 through the drain openings 36. Therefore, in addition to serving as a barrier against drafts and dirt infiltration, the elongated weatherstrip 130 also serves to induce the eflux of collected moisture from the interior of the inner channel 22.

Because of the provision of the continuous weatherstrips 120 and 130, a dual sash sliding window characterized by resistance to infiltration of air, dirt and moisture is attained. The leakage characteristic of prior art constructions is completely eliminated and the self-draining characteristics enhanced by the provision of the elongated weatherstrip in the outer channel in overlying relationship with the drain openings from the inner channel.

I claim:

1. In a window construction, the combination of: a frame having a head and sill each incorporating outer walls and one intermediate wall defining inner and outer channels, said sill having inner and outer tracks, respectively, in said inner and outer channels; an inner sash slidable on said inner track, said inner sash having a first interlocking stile having an interlocking portion thereupon; an outer sash slidable on said outer track, said outer sash having a second interlocking stile having an interlocking portion thereupon interengageable with said interlocking portion on said inner sash, said interlocking portions having clearance openings therein at the opposite extremities thereof for said intermediate walls; an elongated weatherstrip receptacle in one of said stiles disposed externally of the interlocking portion thereof; and vertical weatherstrip means mounted in said receptacle and closing said openings immediately adjacent said intermediate wall.

2. In a window construction, the combination of: a frame having a head and sill each incorporating outer walls and one intermediate wall defining inner and outer channels, said sill having inner and outer tracks, respectively, in said inner and outer channels; an inner sash slidable on said inner track, said inner sash having a first interlocking stile having an interlocking portion thereupon; an outer sash slidable on said outer track, said outer sash having a second interlocking stile having an interlocking portion thereupon interengageable with said interlocking portion on said inner sash, said interlocking portions having clearance openings therein for said intermediate wall; an elongated weatherstrip receptacle in one of said stiles disposed externally of the interlocking portion thereof; and vertical weatherstrip means mounted in said receptacle and closing said openings immediately adjacent said intermediate wall, said weatherstrip means extending from the top to the bottom of the associated stiles, the upper and lower extremities of said weatherstrip closing said openings and projecting transversely of said openings to engage a corresponding surface of said other stile.

3. In a horizontal window construction, the combination of: a frame having a head and a sill, said sill having inner and outer channels, respectively, incorporating inner and outer tracks, said inner channel having drain openings therein; an inner sash slidable on said inner

track; an outer sash slidable on said outer track; a weatherstrip receptacle formed in the inner portion of said outer track below the top of said track; and a horizontal weatherstrip in said receptacle covering said drain openings, said weatherstrip being constituted by an elongated body having a plurality of filamentary elements covering said drain openings.

4. In a sliding window construction, the combination of: a frame having a head and a sill each having an inner and outer channel incorporating inner and outer tracks, said inner channel of said sill having drain openings therein; an inner sash slidable on said inner track having a stile with a first interlock thereupon; an outer sash slidable on said outer track having a stile with a second interlock thereupon engageable with the interlock of said inner sash, said interlocks having clearance openings in the opposite extremities thereof;

5

an elongated vertical weatherstrip receptacle in one of said stiles disposed externally of the interlocks on said stiles; weatherstrip means in said vertical receptacle overlying said openings in said interlocks; a horizontal weatherstrip receptacle formed in the inner portion of said outer track below the top of said track; and a horizontal weatherstrip in said horizontal receptacle overlying said drain openings.
